[57] **ABSTRACT**

Oxidation hair dyeing compositions containing a peroxide source, one or more oxidation dye precursors and arginine or a protein or polypeptide having a high arginine content as essential components.

16 Claims, No Drawings

**DYEING HUMAN HAIR WITH OXIDATION DYES
AND ARGinine OR A PROTAMINE PROTEIN**

BACKGROUND OF THE INVENTION

This invention relates to compositions and processes 5 for coloring hair.

Pre-formed dyes for coloring hair have not gained wide acceptance due to their general failure to impart colors to hair which are sufficiently imitative of natural hair colors. Products which contain reactants (usually H_2O_2 and a dye precursor) which form dyes in situ on the hair through an oxidation process do produce colors which are closely imitative of natural hair color and have attained reasonable commercial success. These latter products, known in the trade as "oxidation dyes," 10 require rather severe oxidizing conditions (e.g., performing the oxidation at H_2O_2 concentrations of 3 percent or more and a pH of 8.5 or higher for time periods in excess of 20 minutes) and high concentrations of dye precursors to produce the desired coloration. For these 15 and other reasons, such dyes can cause skin irritation and sensitization as well as hair damage to some users. Further, the ammonium hydroxide which is generally used to maintain the high pH in these products has an odor which is offensive to most users and is thought to contribute to hair damage and skin irritation and sensitization. Furthermore, even after subjecting the hair to the presently available oxidation dyes the resulting hair 20 colors are often rather unstable and are partially removed by shampooing.

It is an object of this invention to provide an improved oxidation hair dye composition suitable for use on growing hair which is essentially odorless and which leaves the hair colored with shampoo-stable dyes. It is a further object to provide an improved process for coloring hair using oxidation hair dye compositions comprising arginine or a protein or polypeptide of the type herein disclosed, a peroxide and various oxidation dye precursors. These and other objects are obtained by this invention as will become apparent from the following disclosure. The concurrently filed application of Milbrada, entitled "Oxidation Hair Dyes and Process," Ser. No. 129,556, filed Mar. 30, 1971, now abandoned, relates to the use of guanidinium salts in hair dye compositions. The concurrently filed applications of Knohl and Zeffren, entitled "Hair Bleaching Compositions," Ser. No. 129,555, filed Mar. 30, 1971, now abandoned, and "Hair Bleaching Compositions," Ser. No. 129,554, filed Mar. 30, 1971, now abandoned, relate to the use of peroxide in combination with guanidine salts, arginine and arginine-containing proteins to bleach hair.

SUMMARY OF THE INVENTION

The present invention relates to improved oxidation dye compositions for the coloring of hair comprising various oxidation dye precursors, a peroxide, and arginine, or proteins or polypeptides having a high arginine content, and a process for coloring hair using same.

More specifically, the present invention encompasses oxidation hair dye compositions comprising: (1) from about 0.1 percent to about 20 percent by weight of a compound selected from the group consisting of arginine, and protamine proteins and polypeptides containing a major proportion (50 percent, by weight, and greater) of arginine units in their structure, and the peroxide-compatible salts thereof; (2) from about 0.001 percent to about 6 percent by weight of one or more oxidation dye precursors, e.g., compounds se-

lected from the group consisting of:

wherein Y is selected from the group consisting of hydrogen, halogen, nitro, amino, hydroxyl,

and $-SO_3M$ where M is hydrogen, alkali or alkaline earth metal, ammonium or substituted ammonium wherein one or more hydrogens on the ammonium ion 35 is replaced with a 1 to 3 carbon atom alkyl or hydroxy-alkyl radical, R_1 , R_2 , R_3 and R_4 are the same or different from each other and are selected from the group consisting of hydrogen, C_1 to C_4 alkyl and alkenyl and C_6 to C_9 aryl, alkaryl, and aralkyl, R_5 is selected from the 40 group consisting of hydrogen, C_1 to C_4 unsubstituted or substituted alkyl and alkenyl wherein the substituents are selected from those designated as Y, and C_6 to C_9 unsubstituted or substituted aryl, alkaryl and aralkyl wherein the substituents are selected from those designated as Y, and R_6 is selected from the group consisting of hydrogen, and C_1 to C_4 substituted or unsubstituted alkyl and alkenyl wherein the substituents are those defined as Y, and the peroxide-compatible salts thereof; and (3) from about 0.1 percent to about 6 percent by 45 weight of a water-soluble peroxide compound. The 50 compositions herein are formulated as liquids at a pH (aqueous) of about 8 to about 11 prior to application to the hair.

In addition, this invention encompasses a process for 55 coloring hair, especially growing human hair, comprising contacting said hair with a composition comprising arginine or a protein or polypeptide containing a major amount of arginine, or the peroxide-compatible salts thereof, one or more oxidation dye precursors and a 60 water-soluble peroxide compound, at a pH (aqueous) of from about 8 to about 11, all as disclosed herein, and allowing the color to develop (usually 2 to about 60 minutes).

DETAILED DESCRIPTION OF THE INVENTION

The dyeing compositions of this invention are employed on the hair at an optimum pH of from about 8 to about 11, more preferably about 9 to about 10. Although this pH is in the normal range of hair dyeing compositions, an unexpected increase in the stability of

the resulting hair dyes is noted with the present compositions. While not intending to be restricted by theory, it is hypothesized that the arginine or proteins used herein enhance the penetration of the dye precursors into the hair shaft, thereby stabilizing the dye molecules formed by oxidation. Whatever the reason for the improved hair dyeing properties of the present compositions, the improvement is not attributable merely to the pH, but is related to the presence of the arginine compound.

The amino acid, arginine, or its peroxide-compatible salts, as hereinafter detailed, is one essential component of the dyeing compositions of this invention. Alternatively, proteins or polypeptides having a high arginine content can be used herein in place of arginine to provide the enhanced dyeing activity. The pure amino acid, the proteins, the polypeptides containing a major proportion of arginine units, and their respective salts are referred to collectively herein as "arginine compounds". Proteins having a major proportion of arginine units in their structures are members of that class of proteins known as protamines. While it is not possible to specify with certainty the complete structures of each member of this class since few of their amino acid sequences have been determined, the protamine proteins all have several common characteristics. The most distinctive features of this class of proteins are: (a) a low molecular weight, in the range of about 5,000; (b) a high isoelectric point, in the pH range of about 10 to 12; and (c) a high arginine content, in the range from about 50 percent to about 90 percent, by weight, of the total protein. Protamine proteins having a high arginine content suitable for use herein are listed in R. J. BLock and K. W. Weiss, "Amino Acid Handbook," Thomas, Springfield, Illinois (1956), page 260, et seq. Some of the protamine proteins of high arginine content suitable for use herein include: clupein, obtainable from herring; fontinin, obtainable from salmon; salmin, obtainable from salmon, iridin, obtainable from rainbow trout; lacustrin, obtainable from sea trout; gallin, obtainable from fowl; sturin, obtainable from sturgeon; sperm nucleoprotein from mollusks (*Patella coerulea*); and macerated bovine testes. All of the above proteins of the protamine class have an arginine content greater than 50 percent and are suitably employed herein.

Proteins of the type hereinabove described can be subjected to acid or base hydrolysis to yield polypeptides which also have a high arginine content. Such polypeptides are obtained, for example, during the processing of fish and fowl and can be employed in the dyeing compositions of this invention. Again, the exact chemical structure of these polypeptides cannot be specified with certainty in that they have very complex amino acid sequences. As in the case of their parent proteins, which are protamines of the type hereinabove disclosed, the polypeptides useful herein have a molecular weight below about 5,000, are basic (pH 10-12), and have an arginine content of about 50 percent, or greater, by weight.

Since arginine and the protamine proteins and polypeptides having an arginine content of 50%, or greater, are basic, they are often isolated from natural sources in the form of salts. Such salts are suitable for use herein, if their anions are compatible with peroxides. Arginine salts, protamine protein salts and protamine polypeptide salts are formed by reacting these materials with mineral acids such as hydrochloric acid, phos-

phoric acid, carbonic acid, sulfuric acid, nitric acid, etc., and the organic acids such as formic acid, acetic acid, lauric acid, chloroacetic acid and the like, each of which provide anions which are compatible with peroxides. Acids containing metallo-anions and strongly reducing anions, e.g., chromic acid and hydrogen thiocyanate, are not suitable herein in that these anions react with the peroxide.

Reaction of the aforementioned arginine, protamines, etc., with the exemplary acids in appropriate amounts yields salts useful herein. For example, arginine chloride, arginine carbonate, arginine sulfate, salmin sulfate, clupein hydrochloride, iridin phosphate, lacustrin carbonate, gallin carbonate, sturin chloride, sperm nucleoprotein hydrochloride, arginine phosphate, acid hydrolyzed sturin pyrophosphate, arginine nitrate, base hydrolyzed gallin acetate, hydrolyzed lacustrin chloroacetate, and the like are suitable for use in the compositions of this invention.

The arginine, protamine protein, protamine polypeptides, and peroxide compatible salts thereof, are used herein at concentrations from about 0.1 percent to 20 percent, preferably 0.5 percent to about 4 percent by weight of the total dye composition. The phosphates and carbonate salts are preferred for this purpose in that they are self-buffering. Arginine phosphate, arginine carbonate and arginine chloride are preferred. Clupein carbonate and salmin phosphate are also preferred herein.

The oxidation dye precursors which are used in the compositions and processes herein include aromatic diamines, polyhydric phenols, amino phenols and derivatives of these aromatic compounds (e.g., N-substituted derivatives of the amines, and ethers of the phenols). In general terms, oxidation hair dye precursors include those monomeric materials which, on oxidation, form oligomers or polymers having extended conjugated systems of electrons in their molecular structure. Because of the new electronic structure, the resultant oligomers and polymers exhibit a shift in their electronic spectra to the visible range and appear colored. For example, oxidation dye precursors capable of forming colored polymers include materials such as aniline, which has a single functional group and which, on oxidation, forms a series of conjugated imines and guinonoid dimers, trimers, etc. ranging in color from green to black. Compounds such as p-phenylenediamine, which has two functional groups, are capable of oxidative polymerization to yield higher molecular weight colored materials having extended conjugated electron systems, i.e., the so-called "Bandszowski's Base" type of dye compound. Color modifiers, such as those detailed hereinafter, can optionally be used in conjunction with the oxidation dye precursors herein and are thought to interpose themselves in the colored polymers during their formation and to cause shifts in the electronic spectra thereof, thereby resulting in slight color changes. A representative list of oxidation dye precursors suitable for use herein is found in Sagarin, "Cosmetic Science and Technology," Interscience, pages 504 and 508. It is to be understood that arginine and the protamine proteins, polypeptides and peroxide-compatible salts thereof, are suitable for use (in combination with a peroxide as detailed herein) with all manner of oxidation dye precursors and color modifiers and that the precursors detailed below are

only by way of example and are not intended to limit the compositions and processes herein.

The typical aromatic diamines, polyhydric phenols, amino phenols, and derivatives thereof, described above as primary dye precursors can also have additional substituents on the aromatic ring, e.g., halogen, aldehyde, carboxylic acid, nitro, sulfonic acid and substituted and unsubstituted hydrocarbon groups, as well as additional substituents on the amino nitrogen and on the phenolic oxygen, e.g., substituted and unsubstituted alkyl and aryl groups.

Examples of suitable aromatic diamines, amino phenols, polyhydric phenols and derivatives thereof, respectively, are compounds having the general formulas (A), (B) and (C) below:

wherein Y is hydrogen, halogen, (e.g., fluorine, chlorine, bromine or iodine), nitro, amino, hydroxyl,

-COOM or $-\text{SO}_3\text{M}$ (where M is hydrogen or an alkali or alkaline earth metal, ammonium, or substituted ammonium wherein one or more hydrogens on the ammonium ion is replaced with a 1 to 3 carbon atom alkyl or hydroxyalkyl radical), wherein R₁, R₂, R₃ and R₄ are the same or different from each other and are selected from the group consisting of hydrogen, C₁ to C₄ alkyl or alkenyl and C₆ to C₉ aryl, alkaryl or aralkyl, and R₅ is hydrogen, C₁ to C₄ unsubstituted or substituted alkyl or alkenyl wherein the substituents are selected from those designated as Y, above, or C₆ to C₉ unsubstituted or substituted aryl, alkaryl or aralkyl wherein the substituents are selected from those defined as Y, above. Since the precursors of formula (A) are amines, they can be used herein in the form of peroxide-compatible salts, as noted, wherein X represents peroxide-compatible anions of the type hereinbefore detailed. The general formula of the salt indicated is to be understood to encompass those salts having mono-, di-, and tri-negative anions. Specific examples of formula (A) compounds are:

o-phenylenediamine
m-phenylenediamine
p-phenylenediamine
2-chloro-p-phenylenediamine sulfate
2-iodo-p-phenylenediamine
4-nitro-o-phenylenediamine phosphate
2-nitro-p-phenylenediamine
1,3,5-triaminobenzene

- 2-hydroxy-p-phenylenediamine
2,4-diaminobenzoic acid
sodium 2,4-diaminobenzoate
calcium di-2,4-diaminobenzoate
ammonium 2,4-diaminobenzoate
trimethylammonium 2,4-diaminobenzoate
tri-(2-hydroxyethyl)ammonium 2,4-diaminobenzoate
2,4-diaminobenzaldehyde carbonate
2,4-diaminobenzenesulfonic acid
potassium 2,4-diaminobenzenesulfonate
N,N-diisopropyl-p-phenylenediamine bicarbonate
N,N-dimethyl-p-phenylenediamine
N-methyl-N'-(2-propenyl)-p-phenylenediamine
N-phenyl-p-phenylenediamine chloride
15 N-phenyl-N-benzyl-p-phenylenediamine
N-ethyl-N'-(3-ethylphenyl)-p-phenylenediamine
2,4-toluenediamine dinitrate
2-ethyl-p-phenylenediamine
2-(2-bromoethyl)-p-phenylenediamine
20 2-phenyl-p-phenylenediamine laurate
4-(2,5-diaminophenyl)benzaldehyde
2-benzyl-p-phenylenediamine acetate
2-(4-nitrobenzyl)-p-phenylenediamine
2-(4-methylphenyl)-p-phenylenediamine
25 2-(2,5-diaminophenyl)-5-methylbenzoic acid

where X and Y are the same as in formula (A), R₁ and R₂ can be the same or different from each other and are the same as in formula (A), R₅ is the same as in formula (A) and R₆ is hydrogen or C₁ to C₄ substituted or unsubstituted alkyl or alkenyl wherein the substituents are selected from those defined as Y in formula (A). Specific examples of formula (B) compounds are:

o-aminophenol
m-aminophenol
p-aminophenol
2-chloro-p-aminophenol
2-iodo-p-aminophenol
2-nitro-p-aminophenol
3,4-dihydroxyaniline
3,4-diaminophenol chloroacetate
2-hydroxy-4-aminobenzoic acid
60 2-hydroxy-4-aminobenzaldehyde
3-amino-4-hydroxybenzenesulfonic acid
N,N-diisopropyl-p-aminophenol
N-methyl-N-(1-propenyl)-p-aminophenol
N-phenyl-N-benzyl-p-aminophenol sulfate
65 N-methyl-N-(3-ethylphenyl)-p-aminophenol
2-nitro-5-ethyl-p-aminophenol
2-nitro-5-(2-bromoethyl)-p-aminophenol
(2-hydroxy-5-aminophenyl)acetaldehyde

- 2-methyl-p-aminophenol
 (2-hydroxy-5-aminophenyl)acetic acid
 3-(2-hydroxy-5-aminophenyl)-1-propene
 3-(2-hydroxy-5-aminophenyl)-2-chloro-1-propene
 2-phenyl-p-aminophenol palmitate
 2-(4-nitrophenyl)-p-aminophenol
 2-benzyl-p-aminophenol
 2-(4-chlorobenzyl)-p-aminophenol perchlorate
 2-(4-methylphenyl)-p-aminophenol
 2-(2-amino-4-methylphenyl)-p-aminophenol
 p-methoxyaniline
 2-bromoethyl-4-aminophenyl ether phosphite
 2-nitroethyl-4-aminophenyl ether bromide
 2-aminoethyl-4-aminophenyl ether
 2-hydroxyethyl-4-aminophenyl ether
 (4-aminophenoxy)acetaldehyde
 (4-aminophenoxy)acetic acid
 (4-aminophenoxy)methanesulfonic acid
 1-propenyl-4-aminophenyl ether isobutyrate
 (2-chloro)-1-propenyl-4-aminophenyl ether
 (2-nitro)-1-propenyl-4-aminophenyl ether
 (2-amino)-1-propenyl-4-aminophenyl ether
 (2-hydroxy)-1-propenyl-4-aminophenyl ether

where Y, R₅ and R₆ are as defined above in formula (B). Specific examples of formula (C) compounds are:

- o-hydroxyphenol (catechol)
 m-hydroxyphenol (resorcinol)
 p-hydroxyphenol (hydroquinone)
 4-methoxyphenol
 2-methoxyphenol
 4-(2-chloroethoxy)phenol
 4-(2-propenoxy)phenol
 4-(3-chloro-2-propenoxy)phenol
 2-chloro-4-hydroxyphenol (2-chlorohydroquinone)
 2-nitro-4-hydroxyphenol (2-nitrohydroquinone)
 2-amino-4-hydroxyphenol
 1,2,3-trihydroxybenzene (pyrogallol)
 2,4-dihydroxybenzaldehyde
 3,4-dihydroxybenzoic acid
 2,4-dihydroxybenzenesulfonic acid
 3-ethyl-4-hydroxyphenol
 3-(2-nitroethyl)-4-hydroxyphenol
 3-(2-propenyl)-4-hydroxyphenol
 3-(3-chloro-2-propenyl)-4-hydroxyphenol
 2-phenyl-4-hydroxyphenol
 2-(4-chlorophenyl)-4-hydroxyphenol
 2-benzyl-4-hydroxyphenol
 2-(2-nitrophenyl)-4-hydroxyphenol
 2-(2-methylphenyl)-4-hydroxyphenol
 2-(2-methyl-4-chlorophenyl)-4-hydroxyphenol
 3-methoxy-4-hydroxybenzaldehyde
 2-methoxy-4-(1-propenyl)phenol
 4-hydroxy-3-methoxycinnamic acid
 2,5-dimethoxyaniline

Color modifiers are optionally employed in the compositions and processes of this invention and include certain aromatic amines and phenols and derivatives thereof which do not produce color singly, but which modify the color, shade or intensity of the colors devel-

oped by the oxidation dye precursors. Certain aromatic amines and phenolic compounds, and derivatives thereof, including some aromatic diamines and polyhydroxyphenols of the types described by formulas (A), (B) and (C) above, but which are well known in the art not to be suitable oxidation dye precursors, are suitable as color modifiers herein.

The aromatic amines and phenols and derivatives described above as color modifiers can also have additional substituents on the aromatic ring, e.g., halogen, aldehyde, carboxylic acid, nitro, sulfonyl and substituted and unsubstituted hydrocarbon groups, as well as additional substituents on the amino nitrogen, or phenolic oxygen, e.g., substituted and unsubstituted alkyl and aryl groups. Again, peroxide-compatible salts thereof are suitable for use herein.

Examples of aromatic amines, phenols and derivatives thereof are compounds of the general formulas (D) and (E) below:

wherein Z is hydrogen, C₁ and C₃ alkyl, halogen (e.g., fluorine, chlorine, bromine or iodine) nitro,

40 —COOM or SO₃M, (where M is hydrogen or an alkali or alkaline earth metal, ammonium or substituted ammonium wherein one or more hydrogens on the ammonium ion is replaced with a 1 to 3 carbon atom alkyl or hydroxyalkyl radical), wherein R₁ and R₂ are the same

45 or different and are selected from the group consisting of hydrogen, C₁ to C₄ alkyl or alkenyl and C₆ to C₉ aryl, alkaryl or aralkyl and R₇ is hydrogen, C₁ to C₄ unsubstituted or substituted alkyl or alkenyl wherein the substituents are selected from those designated as Z above

50 or C₆ to C₉ unsubstituted or substituted aryl, alkaryl or aralkyl wherein the substituents are selected from those defined as Z above and wherein X is as defined in formula (A). Specific examples of formula (D) compounds are:

55 aniline
 p-chloroaniline sulfate
 p-fluoroaniline
 p-nitroaniline

60 p-aminobenzaldehyde
 p-aminobenzoic acid
 sodium-p-aminobenzoate
 lithium-p-aminobenzoate
 calcium di-p-aminobenzoate
 ammonium-p-aminobenzoate
 trimethylammonium-p-aminobenzoate
 tri(2-hydroxyethyl)-p-aminobenzoate
 p-aminobenzenesulfonic acid

potassium p-aminobenzenesulfonate
 N-methylaniline
 N-propyl-N-phenylaniline chloride
 N-methyl-N-2-propenylaniline
 N-benzylaniline
 N-(2-ethylphenyl)aniline
 4-methylaniline
 4-(2-bromoethyl)aniline
 2-(2-nitroethyl)aniline
 (4-aminophenyl)acetaldehyde
 (4-aminophenyl)acetic acid
 4-(2-propenyl)aniline acetate
 4-(3-bromo-2-propenyl)aniline
 4-phenylaniline chloroacetate
 4-(3-chlorophenyl)aniline
 4-benzylaniline
 4-(4-iodobenzyl)aniline
 4-(3-ethylphenyl)aniline
 4-(2-chloro-4-ethylphenyl)aniline

wherein Z and R₇ are defined as in formula (D) and R₈ is hydrogen or C₁ to C₄ substituted or unsubstituted alkyl or alkenyl wherein the substituents are selected from those defined as Z in formula (D). Specific examples of formula (E) compounds are:

phenol
 p-chlorophenol
 p-nitrophenol
 p-hydroxybenzaldehyde
 p-hydroxybenzoic acid
 p-hydroxybenzenesulfonic acid
 ethylphenyl ether
 2-chloroethylphenyl ether
 2-nitroethylphenyl ether
 phenoxyacetraldehyde
 phenoxyacetic acid
 3-phenoxy-1-propene
 3-phenoxy-2-nitro-1-propene
 3-phenoxy-2-bromo-1-propene
 4-propylphenol
 4(3-bromopropyl)phenol
 2-(2-nitroethyl)phenol
 (4-hydroxyphenyl)acetaldehyde
 (4-hydroxyphenyl)acetic acid
 4-(2-propenyl)phenol
 4-phenylphenol
 4-(3-bromophenyl)phenol
 4-benzylphenol
 4-(3-fluoro-2-propenyl)phenol
 4-(4-chlorobenzyl)phenol
 4-(3-ethylphenyl)phenol
 4-(2-chloro-3-ethylphenyl)phenol
 2,5-xylenol

The oxidation dye precursors can be used herein alone or in combination with other oxidation dye precursors, and one or more dye precursors can be used in combination with one or more color modifiers. The choice of a single dye precursor or of a particular combination of dye precursors and modifiers will be determined by the color, shade and intensity of coloration

which is desired. There are eleven preferred oxidation dye precursors which can be used herein, singly or in combination, to provide oxidation hair dyes having a variety of shades ranging from ash blonde to black; 5 these are: pyrogallol, resorcinol, p-phenylenediamine, o-phenylenediamine, m-phenylenediamine, o-aminophenol, p-aminophenol, 4-amino-2-nitrophenol, nitro-p-phenylenediamine, N-phenyl-p-phenylenediamine and 2,4-diaminoanisole. These can 10 be used in the molecular form or in the form of peroxide-compatible salts, as detailed above.

The concentration of dye precursor (and color modifier, if used) in the coloring solution can be from about 0.001 percent to about 6 percent by weight and is preferably from about 0.01 percent to about 2.0 percent by weight.

A peroxide is required herein at a concentration of about 0.1 percent to about 6.0 percent by weight to develop the color. The peroxide component of the present compositions comprises hydrogen peroxide or any of the water-soluble alkali metal or alkaline earth metal peroxides such as sodium peroxide, potassium peroxide, and the like. In addition, peroxide complexes such as the water-soluble addition compounds of organic materials such as urea with hydrogen peroxide are suitable herein; examples of some of these materials include urea-peroxide, N-methylurea peroxide, and the like. Sodium perborate is also suitable herein as are the organic peroxides, e.g., the organic peroxy acids having 20 the general formula RCOOOH, with R being lower alkyl and phenyl. Preferred are H₂O₂, alkali metal peroxides and urea-peroxide.

As noted hereinabove, the dyes of this invention are 35 used in the basic pH range (pH 8 to 11, preferably 9 to 10). During the course of the dyeing operation the pH of the dye composition will sometimes change; therefore, in a preferred embodiment herein a buffer is included in the composition to maintain a relatively constant pH within the desired range. Any of the common peroxide-stable buffers suitable for use in the pH range from 8 to 11 can be used herein for this purpose, e.g., 40 carbonates, Na₂HPO₄, NaH₂PO₄, etc. Especially preferred herein are phosphate buffers, especially ortho-, meta-, and tri-polyposphate salts. While any of the common buffers are useful herein, the phosphate buffer salts have the advantage that they are innocuous when applied to the skin, are efficient buffers over the pH range indicated, and stabilize the peroxide being 45 used by preventing metal ion catalyzed peroxide decomposition. Buffers such as the phosphates are usually used at concentrations from about 0.1 percent to about 5 percent, by weight, in the present compositions. The carbonate or phosphate salts of arginine or the protamine proteins or polypeptides are self-buffering at the proper pH.

The dye precursors and color modifiers are known to be polymerized when contacted with liquid solutions of peroxides to form colored dye molecules. For this reason, it is necessary in the formulation of the dye compositions of this invention to exclude liquid peroxides therefrom until just prior to application of the compositions to the hair. This can be done, for example, by packaging the dye precursors, arginine or protamines and color modifiers separately from the peroxide; such separate packaging will be required when aqueous solutions of hydrogen peroxide (commercially available) are used herein. Alternatively, a dry peroxide source,

e.g., sodium peroxide, sodium perborate, urea-peroxide, and the like, can be admixed with the dye precursors, color modifiers, arginine, etc., buffer and the like in a dry packet. Such compositions are designed to be added to water or to a carrier liquid as hereinafter noted, just prior to use.

The coloring process of the present invention is preferably carried out in aqueous solution (the term "solution" herein also encompasses fine dispersions or colloids of the reacting and reacted materials) but any liquid carrier medium which does not interfere with the coloring process and is safe for application to the skin can be used. When the dry compositions noted above are used, they are simply dispersed in the chosen carrier liquid by stirring or shaking. When aqueous hydrogen peroxide is used, the arginine or protamine, or salts thereof, dye precursors and color modifiers are simply admixed therewith. Examples of alternative solvents are glycerol, ethanol and formamide. The time of exposure of the hair to the coloring solution can be from a few seconds up to one or more hours but is preferably from about 10 to 40 minutes.

It is recognized also that conventional hair coloring products contain thickeners such as carboxymethylcellulose, surfactants such as the nonylphenoxypolyoxyethylenes, and conditioners such as solubilized lanolin derivatives, and that such ingredients can also be utilized in the practice of the present invention.

In a preferred manner of carrying out the process of the present invention, an aqueous mixture is prepared containing 0.1 percent to 4.0 percent, by weight, of hydrogen peroxide and one or more oxidation dye precursors and optionally one or more color modifiers, the total weight percent of dye precursor in said mixture being from about 0.01 percent to about 2.0 percent. The pH of the mixture is adjusted with the arginine or protamine, and base as needed, and maintained throughout the coloring process within the range of about 8.0 to 11.0, preferably 9 to 10.0, by a suitable means such as by buffering with peroxide-compatible salts (e.g., a mixture of NaH_2PO_4 and Na_2HPO_4). The hair to be colored is immersed in the mixture. After the hair has reached the desired color, (normally in about 5 to 40 minutes) it is removed from the solution, rinsed and dried.

Alternatively, the arginine or protamine proteins and the dye precursors can be formulated together in a composition which can be diluted to the proper usage concentration immediately prior to use. Such compositions comprise the arginine or protamine compound and one or more oxidation dye precursors, and optionally one or more color modifiers. These compositions can be added directly to a buffered solution of hydrogen peroxide immediately before use. Although said compositions can contain only the arginine or protamine compounds, and dye precursor, they normally contain these materials in combination with an inert diluent in order to facilitate handling and measuring. The diluents can be a liquid such as water so as to form a liquid concentrate or they can be solids such as inorganic salts (e.g., sodium chloride, calcium sulfate, etc.) starches, sugars, etc. Normally the total amount of arginine or protamine compound and dye precursor in the compositions will be from about 0.5% to about 60 percent, by weight, the remainder of the composition comprising the diluent materials and optionally such other materials as hair conditioners (e.g., soluble lanolin de-

rivatives), solvents (e.g., ethanol), surfactants, thickeners (e.g., cellulose derivatives), antioxidants for the dye precursors (e.g., sodium sulfite) and the like.

The invention will be illustrated by the following examples, which are not intended to be limiting of the peroxides, dye precursors and arginine and protamine protein and polypeptide compounds useful herein.

EXAMPLE I

Dry Hair Dye Composition

Ingredient	Weight %
p-Phenylenediamine	0.2
Clupein carbonate	5.0
Sodium peroxide	2.0
Sodium carboxymethylcellulose	2.0
Starch	Balance

50.0 g. of the above dry hair dye composition is 20 added to an equivalent weight of water and mixed therewith to provide a dyeing solution comprising 0.1 percent p-phenylenediamine, 2.5 percent clupein carbonate, 1 percent sodium peroxide and 1 percent sodium carboxymethylcellulose. The composition has a pH of about 9. Light blond hair is coated with the thickened dyeing composition immediately after mixing and allowed to stand for about 25 minutes and is dyed a brown color. The dark brown dye is not substantially removed by shampooing.

In the above composition the p-phenylenediamine is 30 replaced by an equivalent amount of o-phenylenediamine, 2,4-toluenediamine, N,N-dimethyl-p-phenylenediamine, N-phenyl-p-phenylenediamine, 4-nitro-o-phenylenediamine, p-aminophenol, m-aminophenol, o-aminophenol, 2-nitro-p-aminophenol, N-methyl-p-aminophenol, 2-amino-1-phenol-4-sulfonic acid, p-methoxy-aniline, 2,5-dimethoxyaniline, p-hydroxyphenol, o-hydroxyphenol, 2-methoxyphenol, 4-methoxyphenol, 3-methoxy-4-hydroxybenzaldehyde, 40 and 3,4-dihydroxybenzaldehyde, respectively, and equivalent hair dyes are secured. Hair dyed with these compositions achieves the colors noted in Table 1, below.

Table 1

Precursor	Precursor Conc.	Initial Hair Color	Final Hair Color
p-Phenylenediamine	0.1%	light blond	drab brown
o-Phenylenediamine	0.1%	light blond	warm brown
2,4-Toluenediamine	0.1%	light blond	warm brown
N,N-Dimethyl-p-phenylenediamine	0.1%	light blond	drab brown
N-Phenyl-p-phenylenediamine	0.1%	light blond	black
4-Nitro-o-phenylenediamine	0.1%	light brown	warm brown
p-Aminophenol	0.1%	light blond	drab brown
m-Aminophenol	0.1%	light blond	warm brown
o-Aminophenol	0.1%	light blond	warm brown
2-Nitro-p-aminophenol	0.1%	light brown	warm brown
N-Methyl-p-aminophenol	0.1%	light blond	gold blond
2-Amino-1-phenol-4-sulfonic acid	0.1%	light blond	gold blond
p-Methoxyaniline	0.1%	light blond	blue-gray
2,5-Dimethoxyaniline	0.1%	light blond	drab brown
p-Hydroxyphenol	0.1%	light blond	drab blond
o-Hydroxyphenol	0.1%	light blond	drab brown
2-Methoxyphenol	0.1%	light blond	gold blond
4-Methoxyphenol	0.1%	light blond	gold-red
3-Methoxy-4-Hydroxybenzaldehyde	0.1%	light blond	drab blond
3,4-Dihydroxybenzaldehyde	0.1%	light blond	red

13
EXAMPLE II

Dark Brown Hair Dye	
Ingredient	Weight, %
p-Aminodiphenylamine	0.05
4-Amino-2-nitrophenol	0.10
p-Aminophenol	0.21
2-Nitro-p-phenylenediamine	0.01
p-Phenylenediamine	2.1
1:1 Fusion mixture of 4-nitro-o-phenylenediamine and 2-nitro-p-phenylenediamine	
Pyrogallol	0.2
Resorcinol	1.4
Sodium sulfite	0.2
Arginine carbonate	20.0
Sodium peroxide	6.0
Sodium carboxymethylcellulose	4.0
Starch	Balance

The above dry dye composition is added to water (1:1 wt. basis) and mixed therewith to provide an odorless, thickened dyeing solution having a pH of about 9.3. Bleached blond hair is coated with said thickened dyeing solution immediately after mixing and allowed to stand for about 40 minutes and is dyed a dark brown color. The dark brown color is not substantially removed by shampooing.

In the above composition the arginine carbonate is replaced by an equivalent amount of arginine phosphate, clupein carbonate, lacustrin carbonate, salmin carbonate, sperm nucleoprotein phosphate, iridin phosphate, macerated bovine testes nitrate, and gallin phosphate, respectively. The respective formulations are applied to bleached blond hair and dye said hair a dark brown color (20-30 minutes) which is not substantially removed by shampooing.

The above dyeing composition is added to glycerol, ethyl alcohol, isopropanol, and 1:1 (wt.) mixtures thereof with water prior to application to the hair and equivalent results are secured.

The above compositions are adjusted to a pH about 11.0 using sodium hydroxide, and triethanolamine, respectively, and equivalent dyes are secured.

The above compositions are added to water at a weight ratio of dye composition to water of 1:3. The resulting hair dyes are applied to bleached hair and allowed to stand for about 30 minutes and the hair is colored a light brown color which is not substantially removed by shampooing.

EXAMPLE III

Ash Blond Hair Dye	
Ingredient	Weight, %
p-Aminodiphenylamine	0.005
o-Aminophenol	0.1
p-Aminophenol	0.025
2-nitro-p-phenylenediamine	0.065
p-Phenylenediamine	0.15
Fusion mixture of 4-nitro-o-phenylenediamine and 2-Nitro-p-phenylenediamine (1:1 wt.)	0.02
Fusion mixture of 2,2-diaminoanisole and p-phenylenediamine (1:2 wt.)	0.11
Hydroquinone	0.007
Pyrogallol	0.5
Resorcinol	0.13
Sodium sulfite	0.05
Salmin carbonate	40.0
Sodium peroxide	4.0

-Continued

Ash Blond Hair Dye		
Ingredient	Weight, %	
5 Sodium carboxymethylcellulose	4.0	
Starch	Balance	

The above composition is admixed with water (1:1 wt. basis) and applied to bleached hair for one hour; excess dye composition is removed from the hair by a water rinse and the hair dyed an ash blond color which is shampoo-stable.

In the above composition, each of the following modifications are made:

15 The sodium peroxide is replaced by an equivalent amount of urea-peroxide, peroxyacetic acid, p-chloroperoxybenzoic acid, and methylperoxyacetic acid, respectively, and equivalent results are secured in that the hair is dyed an ash blond color.

20 The above composition is added to water (1:1 wt. basis) and adjusted to pH 8.0 with hydrochloric acid prior to application to the hair. The hair is dyed to an ash blond color in one hour.

25 The salmin carbonate is replaced by an equivalent amount of clupein, fontin, salmin, iridin, lacustrin, gallin, sturin, sperm nucleoprotein, and macerated bovine testes, respectively, and the pH is adjusted with a sodium hydrogen phosphate buffer to 9.3 and equivalent compositions are secured.

30 The salmin carbonate is replaced by an equivalent amount of clupein carbonate, fontin phosphate, salmin acetate, iridin chloroacetate, lacustrin fluoride, gallin lactate, sturin stearate, sperm nucleoprotein bicarbonate, and macerated bovine testes benzoate, respectively, and equivalent hair dyeing compositions are secured.

35 The p-aminodiphenylamine is replaced by o-phenylenediamine, m-phenylenediamine, 4-amino-2-nitrophenol, nitro-p-phenylenediamine, N-phenyl-p-phenylenediamine, and 2,4-diaminoanisole, respectively, and equivalent results are secured.

40 The pyrogallol concentration is increased to 3.0 percent and the p-phenylenediamine concentration is increased to 1.6 percent and a purplish-black hair dye composition is thereby secured. This composition is mixed (1:1 wt.) with water and applied to the hair for a period of about 10 minutes and provides a purplish-black hair color which is substantially shampoo-stable.

45 50 Hair coloring products employing oxidation hair dyes are typically marketed in kit form, i.e., a package comprising an individually packaged oxidizing component and an individually packaged oxidation dyeing component. In an embodiment of this invention said oxidation component consists of an aqueous solution of a peroxide as detailed herein, most generally aqueous hydrogen peroxide having a concentration from about 0.1 percent to about 6 percent by weight, and said oxidation dyeing component comprises an oxidation dye precursor of the type hereinbefore detailed and an arginine or protamine compound or salt thereof, of the type hereinabove detailed. The components are mixed by the user immediately prior to application to the hair.

An example of such kit is as follows:

55 60 65 A hair dyeing kit is assembled comprising a single package including therein: (1) a 4 oz. bottle of hydrogen peroxide (3 percent by weight H_2O_2); and (2) a foil packet containing an oxidation dyeing component, said

component consisting of 4 g. of p-phenylenediamine, 40 g. of arginine carbonate, 2 g. of sodium carboxymethylcellulose and 10 g. of starch. The oxidation dyeing component is admixed with the hydrogen peroxide and the solution is applied to the hair and provides a brown-black color which is substantially shampooable.

In the above composition the arginine carbonate is replaced by an equivalent amount of arginine phosphate, clupein carbonate, clupein phosphate, salmin carbonate, and salmin phosphate, respectively, and equivalent results are secured.

In the above composition the 3 percent aqueous hydrogen peroxide solution is replaced by an equivalent volume of 0.1% hydrogen peroxide solution and equivalent results are secured.

In the above composition the arginine carbonate in the packet is replaced by 0.1 g. of arginine, 10 g. of clupein, 10 g. of salmin, 1 g. of iridin, 0.01 g. of sperm nucleoprotein and 20 g. of lacustrin, respectively. 5 g. of a buffer (4 g. Na_2HPO_4 , 1 g. of NaH_2PO_4) is included in the packet in each case. The resulting coloring kits are used to dye hair.

In the above coloring kit the level of p-phenylenediamine is reduced to 0.001 g. and a pale brown tint suitable for toning blond hair is secured.

What is claimed is:

1. A hair dye composition comprising: (1) from about 0.1 percent to about 20 percent by weight of a compound selected from the group consisting of arginine, a protamine protein, and a peroxide-compatible salt thereof; (2) from about 0.001 percent to about 6 percent by weight of one or more oxidation dye precursors; (3) from about 0.1 percent to about 6 percent by weight of a water-soluble peroxide compound and (4) an inert diluent.

2. A composition according to claim 1 wherein the protamine protein is selected from the group consisting of clupein fontinin, salmin, iridin, lacustrin, gallin, sturin, sperm nucleoprotein derived from mollusks (*Patella coerulea*), macerated bovine testes, and a peroxide-compatible salt thereof.

3. A composition according to claim 1 wherein the dye precursor is selected from the group consisting of compounds having the formula

and

60

wherein Y is selected from the group consisting of hydrogen, halogen, nitro, amino, hydroxyl,

and $-\text{SO}_3\text{M}$ where M is hydrogen, alkali or alkaline earth metal, ammonium or substituted ammonium wherein one or more hydrogens on the ammonium ion is replaced with a 1 to 3 carbon atom alkyl or hydroxy-

10 alkyl radical, $\text{R}_1, \text{R}_2, \text{R}_3$ and R_4 are the same or different from each other and are selected from the group consisting of hydrogen, C_1 to C_4 alkyl and alkenyl and C_6 to C_9 aryl, alkaryl, and aralkyl, R_5 is selected from the group consisting of hydrogen, C_1 to C_4 unsubstituted or 15 substituted alkyl and alkenyl wherein the substituents are selected from those designated as Y, and C_6 to C_9 unsubstituted or substituted aryl, alkaryl and aralkyl wherein the substituents are selected from those designated as Y, and R_6 is selected from the group consisting of 20 hydrogen, and C_1 to C_4 substituted or unsubstituted alkyl and alkenyl wherein the substituents are those defined as Y, and a peroxide-compatible salt thereof.

4. A composition according to claim 1 wherein the oxidation dye precursor is selected from the group consisting of pyrogallol, resorcinol, p-phenylenediamine, o-phenylenediamine, m-phenylenediamine, o-aminophenol, p-aminophenol, 4-amino-2-nitrophenol, nitro-p-phenylenediamine, N-phenyl-p-phenylenediamine and 2,4-diminoanisole.

5. A composition according to claim 1 also containing from about 0.001 percent to about 6 percent by weight of a color modifier selected from the group consisting of an aromatic amine and a phenolic compound.

6. A composition according to claim 1 wherein the water-soluble peroxide is selected from the group consisting of hydrogen peroxide, an alkali metal peroxide and urea-peroxide.

7. A composition according to claim 1 also containing from about 0.1 percent to about 5 percent by weight of a peroxide-stable buffer capable of maintaining a pH of from about 8 to about 11 in aqueous solution.

8. A hair dye composition comprising: (1) from about 0.5 percent to about 4 percent by weight of a compound selected from the group consisting of arginine carbonate, arginine chloride, arginine phosphate, clupein carbonate and salmin phosphate; (2) from about 0.01 percent to about 2 percent by weight of an oxidation dye precursor selected from the group consisting of pyrogallol, resorcinol, p-phenylenediamine, o-phenylenediamine, m-phenylenediamine, o-aminophenol, p-aminophenol, 4-amino-2-nitrophenol, nitro-p-phenylenediamine, N-phenyl-p-phenylenediamine and 2,4-diminoanisole; (3) from about 0.1 percent to about 6 percent by weight of a water-soluble peroxide compound selected from the group consisting of hydrogen peroxide, an alkali metal peroxide and urea-peroxide and (4) an inert diluent.

9. A hair dye composition comprising: (1) from about 0.1 percent to about 20 percent by weight of a compound selected from the group consisting of arginine carbonate, arginine chloride and arginine phosphate; (2) from about 0.001 percent to about 6 percent by weight of one or more oxidation dye precursors; (3) from about 0.1 percent to about 6 percent by weight of a water-soluble peroxide compound and (4) an inert diluent.

10. A process for dyeing hair comprising applying to said hair a dyeing composition comprising an aqueous solution of (1) from about 0.1 percent to about 20 per-

cent by weight of a compound selected from the group consisting of arginine, a protamine protein, and a peroxide-compatible salt thereof; (2) from about 0.001 percent to about 6 percent by weight of one or more oxidation dye precursors; and (3) from about 0.1 to about 6 percent by weight of a water-soluble peroxide compound, said composition having a pH from about 8 to about 11, and being applied in an amount and for a time sufficient to yield the desired color.

11. A process according to claim 10 wherein the arginine compound is selected from the group consisting of arginine carbonate, arginine chloride and arginine phosphate.

12. A process according to claim 10 wherein the protamine protein is selected from the group consisting of clupein, fontinin, salmin, iridin, lacustrin, gallin, sturin, sperm nucleoprotein derived from mollusks (Patella coerulea), macerated bovine testes, and a peroxide-compatible salt thereof.

13. A process according to claim 10 wherein the oxidation dye precursor is selected from the group consisting of compounds having the formula

wherein Y is selected from the group consisting of hydrogen, halogen, nitro, amino, hydroxyl,

and $-\text{SO}_3\text{M}$ where M is hydrogen, alkali or alkaline earth metal, ammonium or substituted ammonium wherein one or more hydrogens on the ammonium ion is replaced with a 1 to 3 carbon atom alkyl or hydroxy-alkyl radical, R₁, R₂, R₃ and R₄ are the same or different from each other and are selected from the group consisting of hydrogen C₁ to C₄ alkyl and alkenyl and C₆ to C₉ aryl, alkaryl, and aralkyl, R₅ is selected from the group consisting of hydrogen, C₁ to C₄ unsubstituted or substituted alkyl and alkenyl wherein the substituents are selected from those designated as Y, and C₆ to C₉ unsubstituted or substituted aryl, alkaryl and aralkyl wherein the substituents are selected from those designated as Y, and R₆ is selected from the group consisting of hydrogen, and C₁ to C₄ substituted or unsubstituted alkyl and alkenyl wherein the substituents are those defined as Y, and a peroxide-compatible salt thereof.

14. A process according to claim 10 wherein the oxidation dye precursor is selected from the group consisting of pyrogallol, resorcinol, p-phenylenediamine, o-phenylenediamine, m-phenylenediamine, o-aminophenol, p-aminophenol, 4-amino-2-nitrophenol, nitro-p-phenylenediamine, N-phenyl-p-phenylenediamine and 2,4-diaminoanisole.

15. A process according to claim 10 wherein the dyeing composition also contains from about 0.001 percent to about 6 percent by weight of a color modifier selected from the group consisting of an aromatic amine and a phenolic compound.

16. A process according to claim 10 wherein the water-soluble peroxide is selected from the group consisting of hydrogen peroxide, an alkali metal peroxide and urea-peroxide.
